UNITED STATES PATENT OFFICE.

JOHN STONE STONE, OF CAMBRIDGE, MASSACHUSETTS, ASSIGNOR TO STONE TELEGRAPH AND TELEPHONE COMPANY, OF PORTLAND, MAINE, A CORPORATION OF MAINE.

APPARATUS FOR SELECTIVE ELECTRIC SIGNALING.

SPECIFICATION forming part of Letters Patent No. 737,170, dated August 25, 1903.

Application filed August 2, 1902. Serial No. 118,048. (No model.)

To all whom it may concern:

Be it known that I, JOHN STONE STONE, a citizen of the United States, and a resident of Cambridge, in the county of Middlesex and Commonwealth of Massachusetts, have invented certain new and useful Improvements in Apparatus for Selective Electric Signaling, of which the following is a specification.

My invention relates to the art of wireless or space telegraphy—*i. e.*, to the art of transmitting intelligence from one station to another by means of free or unguided electromagnetic signal-waves or waves which are developed by producing electric vibrations in an elevated conductor, preferably vertically elevated, and which are not guided to their destination by wires, as in the system of telegraphy most commonly practiced to-day.

The object of the present invention is to realize a system in which the transmitting-stations may selectively transmit their signals each to a particular receiving-station simultaneously or otherwise without mutual interference.

25 It is also the object of the invention to provide means whereby each of a plurality of transmitting and receiving stations in such a system may be enabled to selectively place itself in communication with any other station to the exclusion of all remaining stations.

30 It is further the object of the present invention to enable the vertical or elevated conductor in such a system to be made the source of electromagnetic waves of any desired frequency independent of its length and other geometrical constants.

35 The fundamental or underlying principles of the present invention are fully described 40 in an application for United States Patent, Serial No. 4,505, filed by me February 8, 1900, and the present invention is, moreover, tributary to an application for United States Patent, Serial No. 44,384, filed by me January 23, 1901. The present specification describes 45 and claims a specific form of the broad inventions described and claimed in the aforesaid applications Serial Nos. 4,505 and 44,384.

By my invention the elevated conductor of

the transmitting-station is made the source 50 of signal-waves of but a single frequency, and the translating apparatus at the receiving-station is caused to be selectively responsive to signal-waves of but a single frequency, so that the transmitting apparatus corresponds 55 to a tuning-fork sending but a single musical tone and the receiving apparatus corresponds to an acoustic resonator capable of absorbing the energy of that single musical tone only. When the elevated conductor is aperiodic, it is adapted to receive or transmit all 60 frequencies, and accordingly a single aperiodic elevated conductor may be associated with a plurality of local circuits each attuned to a different frequency after the manner 65 well known in the art of multiple telegraphy by wire conductors.

When a single elevated conductor is to be made the source of a plurality of signal-waves of different frequencies and when, moreover, 70 these signal-waves are to be simultaneously developed, it is obviously necessary that the trains of waves of different frequencies developed at the elevated conductor shall be independent of each other—*i. e.*, it is necessary 75 that the electric vibrations of one frequency impressed upon the elevated conductor shall not be affected by the act of simultaneously impressing vibrations of another frequency upon the conductor. The 80 manner of developing the individual electric vibrations of a particular frequency described in this specification is such as to insure *per se* the required independence of the vibrations when several different frequencies 85 are simultaneously impressed upon the elevated conductor. Two preferred forms of such arrangement of apparatus will herein-after be described.

When the apparatus at a particular receiving-station is made resonant to the same frequency as that of the electromagnetic waves emanating from a particular transmitting-station, then this receiving-station will respond to and be capable of selectively receiving 90 messages from that particular transmitting-station to the exclusion of messages simultaneously or otherwise sent from other

transmitting-stations in the neighborhood which generate electromagnetic waves of other frequencies. Moreover, by my invention the operator at the transmitting or receiving station may at will adjust the apparatus at his command in such a way as to place himself in communication with any one of a number of stations in the neighborhood by bringing his apparatus into resonance with the frequency employed by the station with which intercommunication is desired.

In order that the vertical conductor at the transmitting-station shall generate electromagnetic signal-waves of a given frequency, 15 I cause the corresponding electric vibrations in the conductor to be of said given frequency, and this in turn I accomplish by producing forced electric vibrations in the vertical conductor in lieu of producing natural vibrations in the conductor, as has heretofore been practiced. In order that the electric translating apparatus at a receiving-station shall be operated by electric waves of a given frequency and by no others, I interpose between the elevated conductor at the receiving-station and the translating devices a circuit or circuits made resonant to the particular frequency of the electromagnetic waves the energy of which it is desired to 30 have operate the translating devices.

Having thus broadly described the nature and object of the invention and having given at some length the electrical principles upon which it is based in the hereinbefore-mentioned applications Serial Nos. 4,505 and 35 44,384, it will suffice to give the following brief statement of the electrical phenomena involved in the operation of the apparatus to be hereinafter more fully specified.

40 If the electrical equilibrium of a conductor be abruptly disturbed and the conductor be thereafter left to itself, electric currents will flow in the conductor which tend to ultimately restore the condition of electrical equilibrium. These currents may be either unidirectional or oscillatory in character, depending upon the relation between the principal electromagnetic constants of the conductor—*i. e.*, upon its electromagnetic and 45 electrostatic capacities and its resistance. In general the determination of the relations which must subsist in order that an oscillatory restoration of equilibrium shall take place in an electric system and the determination of the periods of these oscillations is 50 very difficult; but in certain simple cases the determination of the conditions for an oscillatory restoration of equilibrium and of the period of these oscillations is quite simple.

55 An example of a simple system capable of an oscillatory restoration of equilibrium is to be found in the case of a circuit consisting simply of a condenser and a coil without iron in its core. If a charge of electricity be imparted to the condenser and if electrodes be 60 then connected to the coil, an isochronous oscillatory current will in general be devel-

oped in the circuit in the process of restoration of its equilibrium. Such a simple circuit is known as a system of a single degree 70 of freedom, and the electric oscillations which it supports when its electrical equilibrium is abruptly disturbed and it is then left to itself are known as natural vibrations or oscillations of the system. These vibrations begin 75 with a maximum of amplitude and gradually die away in accordance with what is known as an “exponential” law and are of a single frequency. Such oscillations are simple harmonic with respect to time and are commonly 80 called simple harmonic oscillations or vibrations. When two such simple circuits are associated together inductively, the system so formed is known as a system of two degrees of freedom, and in the oscillatory restoration of equilibrium—*i. e.*, in the natural 85 vibrations of such circuits—the currents are in general not of a single frequency, but in general consist of the superposition of two currents of different frequencies. In general, if n simple circuits be associated together in a system either by conductive or inductive connections a system of at least n degrees of freedom results, and the natural 90 oscillations of such a system will therefore 95 consist of the superposition of at least n currents. It is, moreover, a fact that the components of the oscillations which together constitute the oscillatory restoration of equilibrium of a complex system are in general 100 not the same as those of the separate simple circuits when these circuits are isolated; but the presence of each simple circuit modifies the natural period of each of the other circuits with which it is associated. The inductive association of two circuits increases 105 the natural period of the high-period circuit and decreases the natural period of the low-period circuit. It is, moreover, a fact that during the restoration of electrical equilibrium currents of each of the periods are found 110 in each of the circuits of the connected system.

The natural vibrations which would result in a circuit were it without resistance are 115 termed the “free” vibrations of the circuit. Such vibrations cannot of course be developed in real circuits, but are interesting in the mathematical study of vibrating systems, because of the greater simplicity in the mathematical problem when resistance is ignored and because in the most important practical cases of oscillator-circuits the period of the natural vibration does not differ appreciably from that of the free vibration. 125

The inductive association of two or more circuits need not necessarily result in an appreciable modification of their natural periods, since if the inductances of the circuits be made large compared to their mutual inductances by the addition to the circuits of large auxiliary inductance-coils the natural periods of the circuits will be sensibly the same as if they were isolated from each other. 130

Besides the ability to execute natural vibrations or oscillations electric systems are capable of supporting what are termed "forced" vibrations, and in the case of forced vibrations the period of the vibration is independent of the electromagnetic constance of the circuit and depends only upon the period of the impressed force. Thus if an electromotive force of a given frequency be impressed upon a circuit free from hysteresis, whether it be a simple circuit or a complex of simple circuits, the forced vibrations or currents resulting from this impressed force will also be of the given frequency. If the circuit in which the forced vibrations are developed be a system of a single degree of freedom—for example, an isolated circuit consisting of a suitably-constructed inductance coil and condenser—then the circuit will respond more powerfully to vibratory forces of one particular frequency than to forces of any other frequency. Such a circuit is said to be a "resonant" circuit, and the particular frequency to which it responds most powerfully is said to be the frequency to which the circuit is resonant. If a vibratory force of given amplitude or pressure be impressed upon such a circuit and the frequency or rate of vibration of the force be slowly varied from zero to infinity, the amplitude or strength of the current so developed in the circuit will have but a single maximum and that maximum will occur when the frequency or rate of vibration of the impressed force reaches that to which the circuit is resonant. This frequency is numerically the same as the frequency of the free vibrations of the circuit. If the system in which the forced vibrations are developed be a system of two or more degrees of freedom—for example, a group of simple resonant circuits brought into inductive relation with each other—then the system is in general not truly resonant to any particular frequency, since if a vibratory force of a given amplitude or pressure be impressed upon such a system and the frequency or rate of vibration of the force be slowly varied from zero to infinity the amplitude or strength of the resulting currents will in general have maxima for two or more different frequencies of the impressed force. Such systems are said to be capable of multiple resonance and respond more or less powerfully to two or more frequencies or rates of vibration. The maxima in the amplitude of the currents referred to above are in general by no means so well defined in the case of systems of two or more degrees of freedom, as in the case of the single isolated circuit responding to the frequency of vibration to which it is resonant, and for this reason the ability of a system of several degrees of freedom to respond to any one of the several frequencies to which it is partially resonant may be termed "quasi resonance." If two isolated simple circuits are resonant each to a particular frequency, and if these two simple circuits be brought

into inductive relation to each other to form a system of two degrees of freedom, the resulting system will in general be found to respond more or less strongly to two frequencies, neither of which is, however, the frequency to which either of the simple circuits constituting the system of two degrees of freedom was resonant before the simple circuits were brought into association with each other. In general the higher of the two frequencies to which the system will respond by virtue of its quasi resonance is higher than the higher frequency to which either of the two circuits of which it is composed responded when isolated, and the lower of the two frequencies, to which the system will respond by virtue of its quasi resonance, is lower than the lower of the two frequencies to which either of the two circuits of which it is composed responded when isolated. The inductive association of two or more simple resonant circuits need not, however, necessarily result in an appreciable modification of the frequencies to which the individual circuits respond, nor need it necessarily materially diminish the power of the individual circuits to respond to the particular frequency to which they were resonant when isolated, nor, moreover, need it necessarily increase their susceptibility to frequencies other than those to which they were resonant when isolated, since if the inductances of the circuits be made large compared to their mutual inductances by the addition of large inductance-coils the circuits will in the respects mentioned above be sensibly the same as if they were isolated from each other, and the vibrations developed therein will be simple harmonic vibrations.

The details of the invention may best be described by having reference to the drawings which accompany and form a part of this specification.

The same letters so far as may be represent similar parts in all the figures of my drawings.

Figures 1 and 3 are diagrams illustrative of apparatus whereby several stations may develop independently in a single elevated conductor forced electric vibrations of different frequencies, and thereby give rise to electromagnetic signal-waves of different frequencies. Figs. 2 and 4 are diagrams illustrative of apparatus whereby several receiving-stations may be associated with a single elevated conductor and selectively receive the energy of electromagnetic signal-waves of different frequencies each in a particular electroreceptive or translating device to the exclusion of the energy of electromagnetic waves of different frequencies. Figs. 5, 6, and 7 are illustrative of the tuning-condenser used as a receiver.

In the drawings, V represents an elevated conductor or vertical oscillator.

M M' M'' and M₁ M'₁ M''₁ are induction-coils or transformers.

- L L' L'' and $L_1 L'_1 L''_1$ are auxiliary inductance-coils.
- C C' C'' C''' and $C_1 C'_1 C''_1 C'''_1$ are condensers.
  - B and B_1 are batteries.
  - 5 K and K_1 are coherers or other electroreceptive or electric translating devices.
  - k and k_1 are keys.
  - R and R_1 are relays or other suitable translating devices.
  - 10 - p and p_1 are automatic circuit-interrupters.
  - s and s_1 are spark-gaps.
  - P and P_1 are Planté batteries or condensers of large capacity.
  - E is an earth connection.
  - 15 It is to be understood that in lieu of the batteries and automatic interrupters any source of periodically-varying electromotive force may be used—as, for example, an alternating-current generator such as shown in
  - 20 my Letters Patent Nos. 714,756 and 714,831.
  - 25 In the organization shown in Figs. 1 and 3 the key k controls the supply of energy from the battery B to the circuit B k M'' p . When the key k is depressed, the battery B develops an interrupted current in the primary circuit of the induction or spark coil M'', which by virtue of the action of the condenser C''' develops in the usual manner high-potential differences between the terminals
  - 30 of the secondary of the spark-coil M''. As the potential at the terminals of the secondary of M'' rises the charge in the condenser C'' increases till the potential difference is sufficient to break down the dielectric at the
  - 35 spark-gap s . When this occurs, the condenser C'' discharges through the spark at s , the primary of M'', and the inductance-coil L''. This discharge is oscillatory in character and of very high frequency, as will be explained hereinafter. The spark-gap s and the condenser C'' may, however, be interchanged in position with like result, as shown in my hereinbefore-mentioned Letters Patent. The high-frequency current so developed
  - 40 passing through the primary of M'' induces a corresponding high-frequency electromotive force and current in the secondary of M'', and forced electric vibrations result in the circuit M' L' M C'. The circuit M' L' M C'
  - 45 is made resonant to the same frequency as the circuit L'' s C'' M', and it therefore tends to weed out, and thereby screen, the elevated conductor V from harmonics, which may exist in the current developed in the circuit L'' s
  - 50 C'' M'. This screening action of an interposed resonant circuit is due to the well-known property of such circuits by which a resonant circuit favors the development in it of currents of the frequency to which it is attuned and
  - 55 strongly opposes the development in it of currents of other frequencies. The forced electric vibrations induced in the circuit M' L' M C' in turn induce a corresponding high-frequency electromotive force in the secondary of M. The secondary of M is included in a
  - 60 branch circuit C L M of the elevated conductor V, which branch circuit is also made resonant

to the frequency developed by the circuit L'' s C'' M', and the electromotive forces induced in M therefore give rise to forced electric vibrations of corresponding frequency in the vertical oscillator V C L M E. The energy of these vibrations is not absorbed in the branch $C_1 L_1 M_1$ of the elevated conductor V, because this latter branch is made resonant to a frequency different from that developed by the circuit L'' s C'' M', and therefore different from the frequency of vibration developed in the branch C L M. The circuits L'' s C'' M', M' L' M C', and C L M are each made resonant to the frequency of vibration, which is the frequency of the electromagnetic waves with which the operator of the key k transmits his signals. Correspondingly the circuits $L''_1 s_1 C''_1 M'_1$, $M'_1 L'_1 M_1 C'_1$, and $C_1 L_1 M_1$ are each made resonant to another frequency, which is the frequency of the electromagnetic waves with which the operator of key k_1 transmits his signals. When the key k_1 is depressed, the result is exactly similar to that which results from the depressing of the key k except that the frequencies of the vibrations which result in the elevated conductor, and therefore also of the electromagnetic waves radiated, are different in the two cases. The energy of the vibrations developed in the vertical oscillator V C L M E, when the key k_1 is depressed is not absorbed in the branch C L M E of the elevated conductor V, because this branch is made resonant to a frequency different from that developed by the circuit $L''_1 s_1 C''_1 M'_1$, and therefore different from the vibrations so developed in the branch $C_1 L_1 M_1 E_1$. By virtue of the auxiliary inductance-coils $L' L'' L'_1 L''_1$, designed according to the specifications set forth in my hereinbefore-mentioned Letters Patent, the inductances of the several circuits are made large compared to their mutual inductances, and thus the effects of their mutual inductances are "swamped," and the oscillations developed in the circuits and impressed upon the elevated conductor V are simple harmonic oscillations, and therefore the electromagnetic waves radiated by the elevated conductor are simple harmonic electromagnetic waves.

In Figs. 1 and 3 two stations are shown associated with a single elevated conductor, each station being capable of developing in the elevated conductor electric vibrations of a frequency different from that developed by the other station in said elevated conductor. Careful consideration will show that any desired number of stations may in like manner be associated with a single elevated conductor by means of branch circuits each made resonant to a particular frequency different from the frequency to which any of the other branch circuits is made resonant. Careful consideration will show that the operation must be the same in the case of the organizations illustrated in Figs. 1 and 3, since the apparatus and its disposition is the same in the

two drawings, except that the auxiliary inductance-coils and the condensers are shown as symmetrically disposed in the resonant circuits of Fig. 3, and the two stations in Fig. 3 are serially connected in the vertical oscillator instead of being associated by derived circuits from the elevated conductor to earth, as shown in Fig. 1.

The operation of the receiving stations (shown in Figs. 2 and 4) is as follows: Electromagnetic waves of a given frequency impinging upon the elevated conductor V develop therein corresponding electric vibrations of like frequency. If the frequency of these vibrations be that to which the branch circuit C L M is made resonant, the energy of the vibrations will be received in that branch to the exclusion of the branch C₁L₁M₁, which is made resonant to a different frequency. The energy so received in branch C L M is communicated by means of the induction-coil M to the circuit C' M' L' M, which is made resonant to the same frequency as the branch circuit C L M, and thence the energy is communicated to the circuit C'' L'' M', which is likewise made resonant to the same frequency as that of the branches C' M' L' M and C L M. The energy so received in circuit C'' L'' M' operates an electroreceptive or translating device. (Indicated at K in Fig. 2 and at L" in Fig. 4.) These electric translating devices will hereinafter be more fully specified. If the electromagnetic waves impinging upon the elevated conductor V of Figs. 2 and 4 be of the frequency to which the branch circuit C₁L₁M₁ is made resonant, the energy of the resulting vibration in the elevated conductor V will be received in that branch to the exclusion of the branch C L M, which is made resonant to a different frequency. The energy so received by the branch C₁L₁M₁ will be communicated to the circuit C' M' L' M₁, which is made resonant to the same frequency as the branch C₁L₁M₁ and thence to the circuit C'' M' L' M₁, which is made resonant to the same frequency as the circuits C' M' L' M and C L M. Energy so received causes the operation of an electroreceptive or translating device. (Indicated at C' in Fig. 2 and at K in Fig. 4.)

In the circuit C'' L'' M' of Fig. 4 the element L" serves both as an electroreceptive or translating device and as an auxiliary inductance-coil, by which the circuit C'' L'' M' is made resonant to the desired frequency. It is actuated by the current developed in the circuit, utilizing therefor the kinetic energy of the current. This element will be herein-after more fully described. Suffice it here to say that by its operation the reception of the energy of the waves by the circuit C'' L'' M' is made evident through the motion of the armature a.

In the circuit C'' M' L' M₁ of Fig. 2 the element C' serves both as an electroreceptive or translating device and as a tuning-condenser, by which the circuit C'' M' L' M₁ is made resonant to the desired frequency. It is actuated

by the current developed in its circuit, utilizing therefor the potential energy of the current. This element will be hereinafter more fully described.

When electric oscillations or oscillatory electric currents are developed in the circuit M' L'' C'' P by electromagnetic waves of the frequency to which this circuit is attuned, these electric oscillations or oscillatory electric currents pass through the coherer K, which is shunted around the terminals of the condenser C'', and thereby cause the conductivity of said coherer to be so greatly increased that the current of battery B is enabled to pass through the same. Because the high-frequency oscillatory electric currents developed in circuit M' L'' C'' P are permitted to pass through the coherer and because a difference of electrical potential at the terminals of a coherer or of any other resistance is necessary to enable currents to flow through said coherer or other resistance it may be truly said that a coherer is both a current-operated and a potential-operated electric translating device or "wave-responsive device." In this connection it may be remarked that the condenser-receiver C' ₁, above referred to and hereinafter more fully described, is, properly speaking, also a "current-operated wave-responsive device" or a current-operated electric translating device. The use of a condenser in this relation has been described and claimed in my Letters Patent hereinbefore mentioned and in my Letters Patent No. 714,834, which the Commissioner of Patents required me to divide from this application and is not herein claimed.

Whereas heretofore some attempt has been made to classify wireless-telegraph receivers or wave-responsive devices as current-operated and as potential-operated receivers or wave-responsive devices on the ground that they respond, respectively, to changes in current or to changes in potential, it is herein pointed out that the only logical classification of such wireless-telegraph receivers, wave-responsive devices, electroreceptive, or electric translating devices is with regard to the form of energy whereby they are operated. No instrument whereby electric power is measured can be said to be operated by current alone or by potential alone. Thus an ampere-meter is operated by potential as well as by current and a voltmeter is operated by current as well as by potential. In other words, each is operated by electric energy, which is the product of current by potential. If by virtue of a variable electromotive force *e*, applied to a circuit, a current *i* is caused to flow therein, the energy imparted to the circuit in the time *dt* is the product *e i dt*. The equation of electromotive forces in a circuit containing dissipative resistance, inductance, and capacity is

$$e = R i + L \frac{di}{dt} + \frac{1}{C} \int i dt$$

where e is the applied electromotive force, R is the dissipative resistance, L is the inductance, and C is the capacity. That part of e necessary to overcome the dissipative resistance is $R i$, that part of e necessary to overcome the counter electromotive force of self-induction is $L \frac{di}{dt}$ and that part of e necessary to overcome the counter electromotive force of the condenser is $\frac{1}{C} \int i dt$. The energy imparted to such a circuit in the time dt is, as above stated, $e i dt$.

$$15 \quad e i dt = R i^2 dt + L \frac{di}{dt} i dt + \frac{i dt}{C} \int i dt.$$

That part of this energy $R i^2 dt$ which is used in heating the conductor and which is thus dissipated into heat is called the "dissipative" energy of the electric current. That part of this energy $L \frac{di}{dt} i dt$ which is expended in creating a magnetic field is called the "kinetic" energy of the electric current. That part of this energy $\frac{i dt}{C} \int i dt$ which is expended in

charging the condenser is called the "potential" energy of the electric current. In the case of simple harmonic currents the dissipative energy expended in time $\frac{2\pi}{p}$ is $\frac{R I^2}{2}$, and the kinetic and potential energies expended in time $\frac{2\pi}{p}$ are respectively $\frac{L I^2}{2}$ and

35 $\frac{I^2}{2C}$, I being the maximum value of the current flowing in the circuit.

Examples of electroreceptive devices utilizing in their operation the dissipative energy of the currents developed in the circuits in which they are placed for detecting and measuring electromagnetic waves and for receiving space-telegraph signals are to be found in the following publications: *Proceedings of the American Academy of Sciences*, May 9, 1894, page 218, St. John; *Elektrotechnische Zeitschrift*, XIX Jahrg. Heft 33, August 18, 1898, page 562, Tietz; *L'Eclairage Electrique*, Vol. 17, October 8, 1898, page 72, A. Turpain. I have described an electroreceptive device utilizing in its operation the dissipative energy of the electric current developed in a resonant circuit in my applications for Letters Patent, Serial Nos. 119,211 and 122,853. Examples of electric translating devices utilizing in their operation the kinetic energy of the currents developed in the circuits in which they are placed are to be found in United States Letters Patent No. 663,400, granted December 4, 1900, to E. Wilson and C. J. Evans, and examples of such electric translating devices are also to be found in the following publications: *Proceedings of the Royal Society of London*, Vol. LX, page 184, Rutherford; *Philosophical Transactions of the Royal Society of London*, Vol. CLXXXIX, A. page 1, Rutherford; Cir-

70
cular No. 275, "Condensers and their Applications," March, 1898, Philadelphia, J. G. Biddle.

I have described an electric translating device utilizing in its operation the kinetic energy of the electric current developed in a resonant circuit in this specification. Examples of electric translating devices utilizing in their operation the potential energy of the electric current developed in the circuits in which they are placed are to be found in United States Letters Patent No. 685,957, granted November 5, 1901, to Nicola Tesla 80 and in *Wiedemann's Annalen*, Bande 44, page 74, Bjerknes. I have described an electric translating device utilizing in its operation the potential energy of the electric current developed in a resonant circuit in my 85 Letters Patent Nos. 714,756 and 714,834, dated December 2, 1902.

When the coherer K is cohered, as above explained, the battery B is thereby permitted to develop a current in the circuit $B R M'_1 L''_1 K$, which operates the relay R . Similarly when electric vibrations or oscillations are developed in the circuit $M'_1 L''_1 P_1 C''_1 L''_1$ of Fig. 4 the coherer K_1 is cohered, and the relay R_1 is operated by the current developed 95 by battery B_1 in a circuit $B_1 R_1 K_1 L''_1 M'_1 L''_1$.

The function of the Planté batteries or condensers $P P_1$ is simply to provide a low impedance or short circuit for the electric vibrations, while preventing the batteries $B B_1$ from normally developing a current through the relays $R R_1$, respectively. It should be understood that these Planté batteries or condensers are not essential to the tuning of the circuits in which they are included, and in 105 order that they may not appreciably affect the tuning of the circuits in which they are included, and thereby lower the resonant rise of potential at the plates of the condensers $C'' C''_1$, they must be constructed to 110 have large capacities compared to the capacities of the condensers $C'' C''_1$, as fully explained in my Letters Patent Nos. 714,756 and 714,831. These relays by their operation 115 may cause a telegraphic sounder or other telegraphic receiver to respond, and they may also set in motion a tapper or decoherer by which the coherer is restored to its normal condition of high resistance.

The electroreceptive or translating device 120 shown at C''_1 , Fig. 2, is primarily a tuning-condenser for the circuit $C''_1 L''_1 M'_1$; but it also serves to make evident the presence of electric vibrations in said circuit. It consists of a fixed armature or electrode and a 125 movable armature or electrode. If electrical vibrations be of the frequency to which the circuit is made resonant, the electrodes of C''_1 will be at a difference of potential many times greater than the induced or impressed 130 electromotive force. This difference of potential will cause an attraction between the armatures of C''_1 and will cause the movable armature to approach the fixed armature.

This motion may be utilized to close a local circuit, and thereby operate a telegraphic relay or sounder, or it may be caused to deflect a beam of light reflected from its surface.

5 In Fig. 2 the condenser-receiver is merely shown conventionally; but the form used in practice is shown in Figs. 5, 6, and 7.

In Fig. 5 is shown one form of translating device wherein the light from the lamp 1, reflected by the mirror 2 on the movable armature 3 of the tuning - condenser C''_1 , records the movement of said armature on scale 4 when a current flows in the circuit $M'_1 L''_1 C'''_1$.

15 In Fig. 6 the movable armature 3 closes the circuit of relay or sounder 6 by making contact with the post 9. This local circuit is supplied with any desirable amount of energy from the battery 7 by the connection of its 20 terminals to resistance 8.

In Fig. 7 the condenser C''_1 is shown as forming part of the well-known condenser telephone-receiver 9. Here, as in Figs. 5 and 6, the armature 5 is fixed and the armature 25 3 is movable.

The normal capacity of C''_1 is determined by the condition that it shall serve to tune the circuit with which it is associated, but leaves the dimensions of its armatures and 30 their separation undetermined. In order to get the maximum sensitiveness in the instrument, the separation between the opposing surfaces of the armatures is made as small as practicable, and consequently therefore the 35 area of the armature-surfaces is also a minimum. By these means the entire potential energy of the vibratory current in the circuit $C''_1 L''_1 M'_1$ is made available to operate the 40 electric translating device, and since the armatures are very close to each other the rate of change of the energy produced by the motion of the movable armature is at a maximum. The available force to produce this motion is thus made as great as possible.

45 The electric translating device (illustrated at L''_1 , Fig. 4,) consists of a tuning-coil or auxiliary inductance-coil and a flat movable conducting-armature a , preferably placed in the axis of the coil and with its plane at an 50 angle of $\pi/4$ or forty-five degrees to the axis of the coil in the manner now well known in the art of alternating-current-measuring instruments and described first by Elihu Thomson in United States Patent No. 363,186,

55 May 17, 1887. However, as the energy of the electric oscillations to be detected is exceedingly feeble and the frequencies excessively high the apparatus must be correspondingly delicate. For this reason it is necessary to 60 design this flat movable armature with the view of obtaining the greatest possible lightness, and it is necessary that its suspension have the least possible rigidity. I may therefore use for this purpose a ring of aluminium 65 wire similar to the aluminium ring used by Hertz in 1891 in his investigations of electro-magnetic waves and published in *Wiede-*

mann's Annalen, Vol. 42, page 407, or I may use a silver disk similar to that of the well-known Northrup galvanometer described in the 70

Electrical World, December 18 and 25, 1897, and in *Catalogue B* of "Electrical Measuring Instruments," published by J. G. Biddle, Philadelphia, 1898, page 75, or in *Circular No. 275*, on "Condensers and their Applications," pub- 75

lished by J. G. Biddle, Philadelphia, March, 1898, page 23. When a vibratory current is developed in the circuit $C''_1 L''_1 M'_1$ of Fig. 4, a rapidly-vibratory magnetic field is produced in the coil L''_1 .

This field induces a current in 80 the armature a and causes it to rotate about the axis of suspension through an angle which depends upon the amplitude of the magnetic field, its rate of change, and the torsional rigidity of the support by which the armature is 85 maintained in its normal position.

The movement of the armature a may be made evident by causing it to close a local-battery circuit, and thereby operate a telegraphic receiver, or 90

it may be observed by noting the deflection of 95 a beam of light reflected from its surface.

It is to be noted that this electroreceptive or electric translating device is to be differentiated from a coherer in that no auxiliary mechanisms are required to restore it to nor- 95

mal sensitive condition after the reception of a signal, this being accomplished by the torsional rigidity of its suspension, or, in other words, that it is a "self-restoring electric translating device" or a "self-restoring wave- 100

responsive device," whereas a coherer when once cohered by electric vibrations remains thereafter insensitive to subsequent electric vibrations until tapped or restored to its normal sensitive condition and is not, therefore 105

"constantly receptive." The electroreceptive or electric translating device L''_1 is, on the contrary, a "constantly-receptive electric translating device" or a "constantly-receptive wave- 110

responsive device." This electric translating device is to be distinguished from a filings coherer of the Branly type or an electrolytic anticoherer of the Schaefer, 115

Neugschwenden, or Aschkinass type, or an autocoherer consisting of two members of metal in contact at a single point, or of metal 120

and carbon in contact, by the fact that it is metallically continuous and does not consist of a plurality of members in imperfect electrical contact, between which there necessarily exists an infinitesimal dielectric layer.

Finally, as explained above, this translating device is operated by the magnetic component of the electric oscillations or oscillatory electric currents developed in the circuit in which it is included, or, in other words, it is operated by the kinetic energy of 125

the currents developed in said circuit, which kinetic energy is proportional to the inductance of the coil L''_1 and to the square of the 130

current, so that the indications produced by the flat movable armature are proportional to the total energy absorbed by the receiving-circuit and to the total energy absorbed 135

by the resonant circuit in which the coil L'' is included.

I am aware that on page 23 of *Circular No. 275*, above referred to, a Northrup galvanometer is shown connected in series with a loop of wire about ten meters in diameter and with a condenser which is described as capable of being adjusted so that the circuit may be brought into tune with a second circuit containing a spark-gap, a similar condenser, and a similar loop of wire, whereby the magnetic induction effects of the oscillations created in said second circuit may be observed at a short distance; but such an arrangement is not capable of radiating electromagnetic waves, and, as explained below, such an arrangement is not capable of receiving high-frequency electromagnetic waves. I am aware that on page 24 of said *Circular* a Northrup galvanometer is shown connected in series with a Hertzian resonator designed to be used in conjunction with a Hertzian oscillator and capable of having its constants varied so that the galvanometer will give maximum deflections when the frequency of the electromagnetic waves radiated by the oscillator is that to which the resonator is tuned to respond. This apparatus is designed to be used for the purpose of detecting electromagnetic waves emitted from and received by unclosed circuits—viz., a “Hertzian oscillator” and a “Hertzian resonator”—and is not intended to be used for the purpose of detecting the magnetic induction effects which one closed circuit, having rapidly-oscillating currents produced in it by a transformer, Hertz oscillator, or other suitable means, produces on another closed circuit, as is the case with the apparatus illustrated on page 23 of said *Circular No. 275*. The effects to be obtained by the apparatus shown on page 24 of said *Circular* are the same in kind as those sought in wireless telegraphy, and the means for producing these effects while different from the means described herein are the same as those generally used in wireless telegraphy today in which natural oscillations are created in an elevated conductor containing a spark-gap in series therewith, the period of which oscillations, irrespective of any condenser which may be connected to the spark-gap by conductors of either negligible or appreciable inductance, being determined by the resistance, radiating power, capacity, and the inductance of said elevated conductor. It is not my purpose, however, to use the Northrup galvanometer *per se*, and, in fact, the construction of this galvanometer is such as to preclude its use in the receiving system described herein. For whereas the Northrup galvanometer is described in *Catalogue B*, above referred to, as having twenty, forty, and even one hundred turns of copper wire in its field-coils closely crowded together in the smallest possible space and wound on solid dielectric cores I find it essential to the operativeness of my system to separate the turns of all coils

in order to prevent excessive displacement currents, and I also find it necessary to avoid the use of solid dielectric cores in order to prevent electrostatic hysteresis, as hereinbefore described and as fully set forth in Letters Patent Nos. 714,756 and 714,831. Furthermore, the excessive distributed capacity and inductance reactance of the coils of the Northrup galvanometer due to its mode of construction would effectively prevent the tuning of its circuit to a single frequency, and their high resistance would mask the resonant rise in said circuit, whereas I find that for complete selectivity, as well as the efficient operation of the electric translating device shown at L'' , it is imperative that the latter be placed in a truly resonant circuit.

A Hertzian resonator is not accurately described as a resonant circuit, because it does not have sufficient capacity or inductance to hold in the form of electrification and electromagnetism an appreciable amount of the electrical energy supplied thereto. In the form used by Hertz—merely a rectangular or circular loop of wire provided with a minute spark-gap or merely two wires separated by a spark-gap and each provided with a metallic “wing” or capacity area—the first oscillation, more powerful than the succeeding oscillations, produces a minute spark at the gap; but if it fails to develop sufficient potential difference at the terminals of the gap to break down the dielectric therebetween there is no cumulative action whereby the succeeding oscillations may develop the requisite potential. (See Lodge, *Electrician*, London, November 12, 1897.) Furthermore, a Hertz resonator in a manner similar to a stretched cord or a tuning-fork responds not only to the waves of the fundamental frequency to which it is attuned, but also to waves of all frequencies which are aliquot parts of said fundamental frequency—*i. e.*, to all harmonics—and in general it may be stated that this is true of all electric circuits in which the inductance or capacity, or both, are distributed and not “lumped” or localized, as I have fully set forth in my Letters Patent Nos. 714,756 and 714,831. This phenomenon is aptly described by the term “quasi resonance,” to which I have referred in said Letters Patent, and it is called by Lodge, in referring to his now famous “syn-tonic jar experiment,” “sympathetic resonance” or “syntony.” (See Lodge, *Modern Views of Electricity*, London, 1892, pages 339 and 443.) In such a tuned circuit the curve of variation of current with frequency, other things being equal, shows several maxima, or one for each harmonic frequency, and not, as in the circuits I have herein described, a single maximum for a given frequency. All “resonant” circuits may properly be termed “tuned” circuits, but the converse is by no means true, although I am aware that this distinction has recently been overlooked by some. When two resonant circuits are each

attuned to the same frequency, they may properly be said to be "syntonic;" but because two circuits are syntonic it by no means follows that they are necessarily resonant circuits or that they are attuned to the same frequency to the exclusion of other frequencies. Syntony is a property of two or more systems. Resonance is a property which may be possessed by a single system. Syntony may and in general does involve a multiplicity of periods. Resonance involves only a single periodicity or simple harmonic vibration. If in a group of mechanical or electrical systems one of the systems be permitted to execute its natural vibrations, those other systems in the group which are in syntony with this system will have sympathetic vibrations developed in them. If an electrical system be resonant, it will respond and execute greater vibrations when influenced by a simple harmonic force of one particular frequency than for any other, and it will show no marked tendency to respond to vibratory forces of any other frequency than that to which it is attuned even if these vibrations be of periods which are aliquot parts of the particular period to which the system is attuned. Syntony is a relation which may be established between two or more systems, but which cannot be the property of a single system. Resonance is a property of electrical systems which a system possesses without any reference to any other systems. For a vibratory electromotive force of any frequency other than that of a certain predetermined critical frequency the response of a resonant circuit is extremely feeble. The current depends, other things being equal, upon the frequency, and there is a certain critical frequency at which the said current is a maximum, and any change in the frequency from this point in either direction produces a decreased resulting current. The property of true resonance depends upon the simultaneous presence in the circuit of capacity and inductance, and in order that an electric circuit may have appreciable resonance it is requisite that it possess sufficient capacity and inductance to hold in the form of electrification and electromagnetism an appreciable amount of the electrical energy supplied to it. For this purpose the capacity of the circuit must be lumped or localized capacity, as a condenser, and the inductance must be a lumped or localized inductance, as a coil. Such a circuit was first mathematically investigated by J. Clerk Maxwell in the *London, Edinburgh and Dublin Philosophical Magazine and Journal of Science*, Vol. 35, 1868, page 362, and in *Scientific Papers*, Vol. 2, page 121, the peculiar properties of the circuit having been accidentally discovered by Grove, (*Phil. Mag.*, Vol. 35, 1868, page 184,) and it was afterward rediscovered by Dr. Muirhead and independently investigated by Professor Hopkinson, who was the first to apply the

term "electrical resonance" to the phenomenon. (*Journal of the Society of Telegraph Engineers*, Vol. 13, 1884, page 513.)

70

Although the literature on the subject of electrical resonance is most voluminous, I shall herein set forth a few of the more important contributions thereto: first, Blakesley, *Alternating Currents of Electricity*, Chap. 7; second, Paul Boucherot, *Electricien*, Paris, Vol. 14, 1890, page 1042; third, Lodge, *Electrician*, London, Vol. 26, 1891, page 762; fourth, Fleming, *Jour. Inst. Elec. Engrs.*, Vol. 20, 1891, page 366; fifth, Dr. Louis Dun- 75 can, *Trans. Amer. Inst. Elec. Engr.*, Vol. 9, June 6, 1892; sixth, W. Cam. Reckniewski, *Electricien*, Paris, Vol. 17, 1892, page 317; seventh, Pupin, *Trans. Amer. Inst. Elec. Engr.*, Vol. 10, 1893, page 370; eighth, Webster, *The Theory of Elec. & Mag.*, 1897, pages 491 to 502; United States Patent to Hutin and Leblanc, No. 522,564, July 3, 1894; United States Patent to Paul Boucherot, No. 548,511, October 22, 1895; United States 90 Patents to Pupin, Nos. 640,515 and 640,516, January 2, 1900.

I have fully described the property of a resonant circuit to selectively absorb the energy of currents of the frequency to which it is attuned to the exclusion of the energy of currents of different frequency in the following patents: No. 638,152, November 28, 1899; No. 714,756, December 2, 1902; No. 714,831, December 2, 1902; No. 714,834, December 2, 1902; No. 715,515, December 30, 1902; No. 717,467, December 30, 1902, and also in the following pending applications: application Serial No. 506,316, series of 1880, filed April 4, 1894, and in the divisions thereof, Serial 100 Nos. 147,535, 115,056, and 115,057, series of 1900; in application Serial No. 506,517, series of 1880, filed April 4, 1894, and in the divisions thereof, Serial Nos. 113,249, and 113,343, series of 1900, and in application 105 Serial No. 526,986, series of 1880.

In view of the mass of literature on the subject of electrical resonance there is but one meaning which can be given to this term and but one interpretation for the term "resonant circuit," the properties of which are now generally understood by those skilled in the art to be the properties investigated by Maxwell, Hopkinson, Lodge, and others above cited, although I am aware that it has recently been 115 held by some that an elevated conductor connected in series with an inductance-coil, which of course possesses lumped or localized inductance, is resonant to the frequency determined by the capacity of the elevator-conductor, which of course is distributed capacity and the lumped inductance of said coil. It has been even alleged in all seriousness that the capacity of the elevated conductor or aerial is lumped or localized and not distributed, 120 because of the high frequency of the electromagnetic waves received by said aerial and because the length of the aerial is merely a fraction of the wave length of the received 125 130

waves. The fallacy of this must be apparent upon mature consideration, because lumped capacity does not mean lumped as compared to the wave length, but lumped as compared to the inductance, just as distributed capacity does not mean distributed as compared to the wave length, but distributed as compared to the inductance. If the aerial conductor possesses lumped capacity for the reason above alleged by a parity of reasoning it must also possess lumped inductance, and the logical conclusion of the whole matter is that every aerial heretofore considered aperiodic is resonant to waves of some predetermined critical frequency by virtue of this alleged lumped capacity and lumped inductance without the interposition of condensers or coils, whereas experience teaches, on the contrary, that such a circuit, like a stretched cord or a Hertzian resonator, responds not only to a certain fundamental frequency, but to all frequencies which are aliquot parts of said fundamental. In a resonant circuit the kinetic energy and the potential energy are equal. The kinetic energy of a simple circuit is represented by the expression

$$\frac{1}{2} L i^2 = \frac{1}{2} L \left(\frac{E}{R}\right)^2$$

and its potential energy is represented by the expression $\frac{1}{2} C V^2$, where L is the inductance in Henries, C the capacity in Farads, V the potential difference at the terminals of the condenser, and i the current flowing in the circuit, is equal to the impressed electromotive force E divided by the ohmic resistance R of the circuit. From this it follows that in the case of resonance

$$40 \quad \frac{1}{2} L \left(\frac{E}{R}\right)^2 = \frac{1}{2} C V^2, \text{ or } \frac{V}{E} = \sqrt{\frac{L}{C R^2}}$$

which shows that the ratio of the resonant rise of the potential at the terminals of the condenser to the impressed electromotive force, or, in other words, the "selectance" or the "selectivity" of the circuit—i. e., its ability to differentiate currents of the frequency to which it is attuned from currents of all other frequencies—is highest or sharpest when the inductance is great as compared to the capacity and resistance, as I have pointed out in my Letters Patent Nos. 714,756 and 714,831.

55 I am aware that in a paper entitled "The Possibilities of Wireless Telegraphy," published in the *Transactions of the American Institute of Electrical Engineers*, Vol. 16, 1899, page 607, there is described a receiving apparatus for electromagnetic waves comprising an aluminium-wire ring similar to the aluminium-wire ring employed by Hertz (*Wiedemann's Annalen*, Vol. 42, page 407) suspended so that its plane makes an angle of forty-five degrees with the axis of a coil in a manner substantially identical with the sil-

ver disk of the Northup galvanometer. However, this coil does not form part of a closed resonant circuit, as no condenser is shown in the diagram on page 612 illustrating this apparatus, and while the use of a condenser is described the disposition of such condenser with respect to the coil taken in connection with the subjoined statement in the text—viz., that for a given "voltage" the opposition to the current is reduced to the ohmic resistance of the circuit—is such as to preclude the inference that it was the intention of the author to construct or describe a resonant circuit. I am aware that in the *Electrical World and Engineer*, Vol. 34, August 12, 1899, page 239, a somewhat similar apparatus is described by the same author; but in the figure illustrating this paper the condenser is shown in series with the elevated conductor and galvanometer-coil, and no specifications are given for any proportionment of the capacity of this condenser and the inductance of this coil sufficient to justify the inference that a resonant circuit was contemplated. Furthermore, the disposition of the condenser in the system described in this paper is such as to increase the energy dissipated in the vertical wire, and thus defeat the advantage alleged in the American Institute paper for the condenser in shunt to the coil. I am aware that in the *Electrical World and Engineer*, Vol. 34, September 16, 1899, page 421, a somewhat similar receiving apparatus is described. In one of the forms illustrated in this paper a condenser is shown shunting the galvanometer-coil, but in the context there is nothing to indicate that the capacity of the condenser is so related to the inductance of the coil that the circuit containing the condenser and coil is resonant and responds to currents or oscillations of one predetermined critical frequency to the exclusion of currents of other frequencies.

By means of a closed resonant circuit containing a condenser and inductance-coil correlated, as hereinbefore set forth, I am enabled to absorb the energy of electric oscillations created in the elevated conductor by electromagnetic waves of one frequency to the exclusion of the electric oscillations created therein by electromagnetic waves of other frequencies, and I am enabled to develop in this closed resonant circuit currents of maximum amplitude when the oscillations created therein are of the frequency to which the circuit is resonant, and thus I am enabled to obtain appreciable deflections of the flat movable armature *a* by electromagnetic waves of the proper frequency transmitted from a far-distant transmitting-station containing a source of persistent or maintained electromagnetic radiation.

In constructing the various parts of the apparatus shown and described in this specification there is great latitude as to the special forms that may be given them; but it

must be remembered that when a circuit is to be made resonant and it is desired to gain a high degree of resonance both electrostatic and electromagnetic hysteresis must be carefully excluded from the resonant circuit. For this reason all iron should be excluded from the coils in the resonant circuits and solid dielectrics should not ordinarily be employed in the condensers. These injunctions apply to the construction of circuits made resonant to very high frequencies, but not with the same force to the construction of circuits to be resonant to low frequencies. Another precaution to be taken in the construction of the apparatus included in the resonant circuits when very high frequency currents are employed is that conductors between which there exists considerable potential difference during the operation of the apparatus shall be kept as far apart as practicable, because of the excessive displacement-currents which tend to flow in the case of high frequencies. For this reason I so design the coils used in the resonant circuit that their potential energy is small compared to their kinetic energy when supporting a current of the frequency to which the resonant circuit in which they are included is made resonant. The precautions to be observed in designing the coils and condensers so as to exclude electrostatic and electromagnetic hysteresis are fully set forth in my Letters Patent Nos. 714,756 and 714,831. In this way the frequency of the gravest of the natural modes of vibration of the coil itself is made very great compared to the frequency to which the circuit in which the coil is included is made resonant.

- Having described my invention, I claim—
- 40 1. In a system of selective electric signaling by means of electromagnetic waves without connecting-wires between the transmitting and receiving stations, means for independently impressing electric vibrations of different frequencies upon a single elevated conductor, comprising branch circuits conductively connected with said elevated conductor and made resonant each to one of said different frequencies.
  - 45 2. In a system of selective electric signaling by means of electromagnetic waves of different frequencies without connecting-wires between the transmitting and receiving stations, a single elevated conductor in which the energy of the electromagnetic waves of the different frequencies is received, and branch circuits conductively associated with said elevated conductor and made resonant each to one of said different frequencies.
  - 50 3. In a system of selective electric signaling by means of electromagnetic waves without connecting-wires between the transmitting and receiving stations, means for impressing electric vibrations of a predetermined frequency upon an elevated conductor comprising at its lower end a circuit conductively connected with said elevated conduc-

tor and made resonant to the frequency of said electric vibrations.

4. In a system of selective electric signaling by means of electromagnetic waves of a definite frequency without connecting-wires between the transmitting and receiving stations, an elevated conductor in which the energy of electromagnetic waves of said definite frequency is received and a circuit conductively associated with said elevated conductor and made resonant to the frequency of said waves.

5. In a system of space telegraphy, a metallically-continuous elevated conductor, comprising branch circuits conductively connected with said elevated conductor and made resonant each to a different frequency.

6. In a system of space telegraphy, a metallically-continuous elevated conductor comprising at its lower end a circuit conductively connected with said elevated conductor and made resonant to a certain selected and predetermined frequency.

7. In a system of space telegraphy, a metallically-continuous elevated conductor, serially connected with a plurality of closed resonant circuits, each attuned to a different frequency.

8. In a system of space telegraphy, a metallically-continuous elevated conductor, serially connected with a closed resonant circuit attuned to a certain selected and predetermined frequency.

9. In a system of space telegraphy, an elevated conductor conductively connected with a closed resonant circuit attuned to a certain selected and predetermined frequency.

10. In a system of space telegraphy, means for generating electric energy of relatively low frequency and relatively low potential, means for transforming said energy into energy of high frequency and high potential and means for impressing or forcing said energy of high frequency and high potential upon a circuit conductively connected to an elevated conductor and made resonant to said high frequency.

11. In a system of space telegraphy, means for generating electric energy of relatively low frequency and relatively low potential, means for transforming said energy into energy of high frequency and high potential and means for impressing or forcing said energy of high frequency and high potential upon a closed circuit conductively connected to an elevated conductor and made resonant to said high frequency.

12. In a system for developing electromagnetic signal-waves, means for developing electric oscillations in a closed, persistently-oscillating circuit having symmetrically-disposed sources of capacity and inductance and means for impressing or forcing said electric oscillations upon an elevated conductor.

13. In a system for receiving the energy of electromagnetic signal-waves, an elevated conductor and a closed circuit resonant to the

frequency of the waves, the energy of which is to be received, and having symmetrically-disposed sources of capacity and inductance.

14. In a system for receiving the energy of electromagnetic signal-waves, a closed circuit resonant to the frequency of the waves, the energy of which is to be received, an electric translating device shunted around the terminals of one of the elements of said resonant circuit, a local circuit containing a battery and a signal-indicating device in series with said electric translating device and a portion of said resonant circuit, and an electrolytic cell for preventing the normal closure of said local circuit while offering a low impedance to the high-frequency oscillations developed in the resonant circuit.

15. In a system for receiving the energy of electromagnetic signal-waves, a local circuit, containing a signal-indicating device and a battery, and an electrolytic cell for preventing the normal closure of said local circuit.

16. In a system for receiving the energy of electromagnetic signal-waves of a definite frequency, an elevated conductor comprising at its lower end a circuit conductively connected to said elevated conductor and resonant to the frequency of the waves the energy of which is to be received, and means for conveying the energy of the electric oscillations developed in said circuit to an electric translating device.

17. In a system for selectively receiving the energy of electromagnetic signal-waves of different frequencies, an elevated conductor comprising at its lower end a plurality of circuits conductively connected to said elevated conductor and resonant each to one of said different frequencies, and means for conveying the energies of the electric oscillations developed in said circuits, each to a separate electric translating device.

18. In a system for receiving the energy of electromagnetic signal-waves of a definite frequency, an elevated conductor comprising at its lower end a closed circuit conductively connected to said elevated conductor and resonant to the frequency of the waves the energy of which is to be received, and means for conveying the energy of the electric oscillations developed in said circuit to an electric translating device.

19. In a system for selectively receiving the energy of electromagnetic signal-waves of different frequencies, an elevated conductor comprising at its lower end a plurality of closed circuits conductively connected to said elevated conductor and resonant each to one of said different frequencies, and means for conveying the energies of the electric oscillations developed in said circuits, each to a separate electric translating device.

20. In a system for developing electromagnetic signal-waves of a definite frequency, an elevated conductor comprising a circuit conductively connected to said elevated conductor and made resonant to said definite fre-

quency and means for developing in said circuit electric vibrations of corresponding frequency.

21. In a system for receiving the energy of electromagnetic signal-waves of a definite frequency, an elevated conductor comprising a circuit conductively connected to said elevated conductor and made resonant to the frequency of the waves, the energy of which is to be received, and a resonant circuit or a group of resonant circuits associated with the first-mentioned circuit and attuned to the same frequency as said circuit.

22. In a system for independently developing electromagnetic signal-waves of different frequencies, an elevated conductor comprising circuits conductively connected to said elevated conductor and made resonant each to one of said different frequencies and means for independently developing in each said circuit electric vibrations of the frequency to which it is attuned.

23. In a system for selectively receiving the energy of electromagnetic signal-waves of different frequencies, an elevated conductor comprising circuits conductively connected to said elevated conductor and made resonant each to the frequency of a different one of the trains of waves, the energy of which is to be received, and a resonant circuit or group of resonant circuits, each associated with one of the first-mentioned resonant circuits and each attuned to the same frequency as the circuit with which it is associated.

24. In a system for developing electromagnetic signal-waves of a definite frequency, an elevated conductor comprising a circuit conductively connected to said elevated conductor and made resonant to said definite frequency, a source of electrical energy and the group of resonant circuits interposed between the first-mentioned resonant circuit and said source of electrical energy, said circuits being attuned to the frequency of the waves to be developed.

25. In a system for receiving the energy of electromagnetic signal-waves of a definite frequency, an electric translating device, an elevated conductor comprising a circuit conductively connected to said elevated conductor and resonant to the frequency of the waves, the energy of which is to be received, and a resonant circuit or a group of resonant circuits interposed between said electric translating device and the first-mentioned resonant circuit and attuned to the frequency of said waves.

26. In a system for selectively receiving the energy of electromagnetic signal-waves of different frequencies, an elevated conductor comprising a plurality of circuits conductively connected to said elevated conductor and made resonant each to the frequency of a different one of the trains of waves, the energy of which is to be received, and a plurality of resonant circuits, each associated with a different one of said first-mentioned reso-

nant circuits and attuned to the same frequency as the circuit with which it is associated.

27. In a system for developing free or unguided simple harmonic electromagnetic signal-waves of a definite frequency, an elevated conductor comprising a circuit conductively connected to said elevated conductor and made resonant to said definite frequency and means for developing in said circuit forced simple harmonic electric vibrations of corresponding frequency.

28. In a system for receiving the energy of free or unguided simple harmonic electromagnetic signal-waves of a definite frequency, to the exclusion of the energy of signal-waves of other frequencies, an elevated conductor comprising a circuit conductively connected to said elevated conductor and made resonant to the frequency of the waves, the energy of which is to be received.

29. In a system for receiving the energy of free or unguided simple harmonic electromagnetic signal-waves of a definite frequency, to the exclusion of the energy of signal-waves of other frequencies, an elevated conductor comprising a circuit conductively connected to said elevated conductor and made resonant to the frequency of the waves, the energy of which is to be received, and a resonant circuit or group of resonant circuits, associated with the first-mentioned circuit and attuned to the same frequency as said circuit.

30. In a system for independently developing free or unguided simple harmonic electromagnetic signal-waves of different frequencies, an elevated conductor comprising circuits conductively connected to said elevated conductor and made resonant each to one of the said different frequencies and means for independently developing in said circuits forced simple harmonic electric vibrations of different and corresponding frequencies.

31. In a system for selectively receiving the energy of free or unguided simple harmonic electromagnetic signal-waves of different frequencies, each to the exclusion of the rest, an elevated conductor comprising circuits conductively connected to said elevated conductor and made resonant each to the frequency of a different one of the trains of waves, the energy of which is to be received.

32. In a system for selectively receiving the energy of free or unguided simple harmonic electromagnetic signal-waves of different frequencies, each to the exclusion of the rest, an elevated conductor comprising circuits conductively connected to said elevated conductor and made resonant each to the frequency of a different one of the trains of waves, the energy of which is to be received, and a resonant circuit or group of resonant circuits each associated with one of the first-mentioned resonant circuits and each attuned to the same frequency as the circuit with which it is associated.

33. In a system for developing free and un-

guided electromagnetic signal-waves of a definite frequency, an elevated conductor comprising a circuit conductively connected to said elevated conductor and made resonant to said definite frequency, a source of electrical energy and a group of resonant circuits interposed between the first-mentioned circuit and said source of electrical energy, said circuits being attuned to the frequency of the waves to be developed.

34. In a system for receiving the energy of free or unguided simple harmonic electromagnetic signal-waves of one frequency to the exclusion of the energy of signal-waves of other frequencies, an electric translating device, an elevated conductor comprising a circuit conductively connected to said elevated conductor and resonant to the frequency of the waves, the energy of which is to be received, and a resonant circuit or a group of resonant circuits interposed between said electric translating device and the first-mentioned resonant circuit and attuned to the frequency of said waves.

35. In a system for selectively receiving the energy of free or unguided simple harmonic electromagnetic signal-waves of different frequencies, each to the exclusion of the rest, an elevated conductor comprising a plurality of circuits conductively connected to said elevated conductor and made resonant each to the frequency of a different one of the trains of waves, the energy of which is to be received, and a plurality of resonant circuits, each associated with a different one of said first-mentioned resonant circuits and attuned to the same frequency as the circuit with which it is associated.

36. In a system for developing free or unguided simple harmonic electromagnetic signal-waves, a condenser, means for charging and discharging said condenser through a closed circuit having inductance adapted to produce under such conditions simple harmonic electric vibrations, and means for communicating the vibrations so produced to an open circuit or elevated conductor comprising a circuit conductively connected to said elevated conductor and made resonant to said vibrations.

37. In a system for developing free or unguided, simple harmonic, electromagnetic signal-waves, a condenser, means for charging and discharging said condenser through a closed circuit having inductance adapted to produce under such conditions simple harmonic electric vibrations, means for communicating said vibrations to a resonant circuit or group thereof attuned to the frequency of these vibrations and means for communicating the resulting electric vibrations in said resonant circuit or group thereof to an open circuit or elevated conductor comprising a circuit conductively connected to said elevated conductor and made resonant to the frequency of said vibrations.

38. In a system for developing free or un-

- guided, simple harmonic, electromagnetic signal-waves, a condenser, means for charging and discharging said condenser through a closed circuit having symmetrically-disposed 5 sources of inductance adapted to produce under such conditions simple harmonic electric vibrations, and means for communicating the vibrations so produced to an open circuit or elevated conductor.
- 10 39. In a system for receiving the energy of electromagnetic signal-waves, an elevated conductor comprising a circuit conductively connected to said elevated conductor and made resonant to the frequency of the waves, 15 the energy of which is to be received, and an electric translating device forming one of the tuning elements of a second resonant circuit, associated with the first-mentioned resonant circuit and attuned to the same frequency 20 as said circuit, said electric translating device being adapted to utilize in its operation the energy of the electric oscillations developed in said second resonant circuit.
- 25 40. In a system for receiving the energy of electromagnetic signal-waves, an elevated conductor comprising a circuit conductively connected to said elevated conductor and made resonant to the frequency of the waves, the energy of which is to be received, and an 30 electric translating device adapted to utilize in its operation the energy of the oscillations developed in a second resonant circuit, associated with the first-mentioned resonant circuit and attuned to the same frequency as 35 said circuit.
- 40 41. In a system for receiving the energy of electromagnetic signal-waves, an elevated conductor comprising a circuit conductively connected to said elevated conductor and made resonant to the frequency of the waves, the energy of which is to be received, and an 45 electric translating device forming one of the tuning elements of a second resonant circuit, associated with the first-mentioned resonant circuit and attuned to the same frequency as 50 said circuit.
- 50 42. In a system for receiving signals transmitted by electromagnetic waves, an electric translating device constituting one of the 55 tuning elements of a closed resonant circuit and adapted to utilize in its operation, the energy of the magnetic component of the electric oscillations developed in said resonant circuit, said resonant circuit being attuned to the frequency of the transmitted waves.
- 55 43. In a system for receiving signals transmitted by electromagnetic waves, an electric translating device constituting one of the tuning elements of a closed resonant circuit 60 and adapted to utilize in its operation, the kinetic energy of the currents developed in said resonant circuit, said resonant circuit being attuned to the frequency of the transmitted waves.
- 60 44. In a system for receiving signals transmitted by electromagnetic waves, the combination of a closed resonant circuit attuned to

the frequency of the transmitted waves and an electric translating device constituting one of the tuning elements of said closed resonant circuit and adapted to utilize in its operation the kinetic energy of the electric oscillations developed therein. 70

45. In a system for receiving signals transmitted by electromagnetic waves, the combination of a closed resonant circuit attuned to the frequency of the transmitted waves and an electric transmitting device adapted to utilize in its operation the kinetic energy of the currents developed in said closed resonant circuit. 75

46. In a system for receiving signals transmitted by electromagnetic waves, the combination of a closed resonant circuit attuned to the frequency of the transmitted waves and an electric transmitting device adapted to utilize in its operation the energy of the magnetic component of the electric oscillations developed in said closed resonant circuit. 80

47. In a system for receiving signals transmitted by electromagnetic waves, the combination of a closed resonant circuit attuned to the frequency of the transmitted waves and a metallically-continuous electric translating device adapted to utilize in its operation the kinetic energy of the currents developed in said resonant circuit. 85

48. In a system of space telegraphy, the combination of means located at a sending-station for radiating electromagnetic waves, 100 an elevated conductor at a receiving-station, a closed circuit resonant to the frequency of the waves, the energy of which is to be received, associated with said elevated conductor, an electric translating device adapted to directly translate the energy of the currents developed in said closed resonant circuit by the electromagnetic waves into the energy of motion, and means for observing such motion. 105

49. In a system for absorbing the energy of electromagnetic waves of one frequency to the exclusion of the energy of like waves of a different frequency, a closed circuit resonant to the frequency of the waves, the energy of which is to be absorbed, and an electric translating device adapted to utilize in its operation the kinetic energy of the currents developed in said closed circuit. 110

50. In a system for absorbing the energy of simple harmonic electromagnetic waves of one frequency to the exclusion of the energy of like waves of a different frequency, a closed circuit resonant to the frequency of the waves, the energy of which is to be absorbed, and an electric translating device adapted to utilize in its operation the kinetic energy of the currents developed in said closed circuit. 115

51. In a system for the transmission of energy by electromagnetic waves of a certain predetermined frequency, a transmitting system comprising a sonorous or closed persistently-oscillating circuit conductively connected to an elevated conductor, said system being adapted to radiate electromagnetic 120

waves of the desired frequency, in combination with a receiving system comprising a closed circuit, resonant to the frequency of the radiated waves.

- 5 52. In a system of signaling by electromagnetic waves, the combination of means at a sending-station for radiating electromagnetic waves and a receiving system at a receiving-station comprising a closed circuit, resonant 10 to the frequency of the transmitted waves, and an electric translating device adapted to utilize in its operation the kinetic energy of the electric currents developed in said closed circuit.
- 15 53. In a system for receiving the energy of electromagnetic waves, an elevated conductor containing the primary of a transformer, an electric translating device in series with a closed resonant circuit and adapted to utilize 20 in its operation the kinetic energy of the currents developed in said closed resonant circuit, and a second closed resonant circuit inductively related to the primary of said transformer and the first-mentioned closed resonant circuit, said circuits being resonant to 25 the frequency of the transmitted waves.

54. A system of signaling by electromagnetic waves having in combination therewith a closed circuit resonant to the frequency of 30 the electromagnetic waves to which it is desired to respond and an electric translating device adapted to utilize in its operation the kinetic energy of the currents developed in said closed circuit.

- 35 55. In a system of signaling by electromagnetic waves, the combination of a closed resonant circuit, attuned to the frequency of the transmitted waves, and an electric translating device adapted to utilize in its operation 40 the kinetic energy of the currents developed in said resonant circuit and to give indications proportioned to the total energy developed therein.

56. In a system of signaling by electromagnetic waves, an apparatus for utilizing the energy of said waves, said apparatus including in combination an elevated conductor for absorbing the energy of said waves whereby electric currents are developed therein by 50 each wave, means for conveying or translating said electric currents to a closed circuit, resonant to the frequency of the transmitted waves, whereby the current-flow is caused to be persistent and the currents developed by 55 successive waves are coördinated so that they act cumulatively upon each other and produce an increased or reinforced resultant current-flow, and means operated by said resultant current-flow to produce a sensible effect or indication.

57. In a system of signaling by electromagnetic waves, a closed circuit resonant to the frequency of the electromagnetic waves, the energy of which is to be received, and a constantly-receptive electric translating device 65 adapted to utilize in its operation the kinetic energy of the currents developed in said resonant circuit.

58. In a system of signaling by electromagnetic waves, a closed circuit resonant to the 70 frequency of the waves, the energy of which is to be received, and a constantly-receptive, self-restoring electric translating device adapted to utilize in its operation the kinetic energy of the currents developed in said resonant circuit.

59. In a system of signaling by electromagnetic waves, a closed circuit resonant to the frequency of the waves, the energy of which is to be received, and a self-restoring electric 80 translating device adapted to utilize in its operation the kinetic energy of the currents developed in said resonant circuit.

60. In a system of signaling by electromagnetic waves, a closed circuit resonant to the 85 frequency of the electromagnetic waves, the energy of which is to be received, and a constantly-receptive electric translating device adapted to utilize in its operation the kinetic energy of the currents developed in said resonant circuit, in combination with a source of 90 maintained or persistent electromagnetic radiation at a sending-station.

61. In a system of signaling by electromagnetic waves, a closed circuit resonant to the 95 frequency of the waves, the energy of which is to be received, and a constantly-receptive, self-restoring electric translating device adapted to utilize in its operation the kinetic energy of the currents developed in said resonant circuit, in combination with a source of 100 maintained or persistent electromagnetic radiation at a sending-station.

62. In a system of signaling by electromagnetic waves, a closed circuit resonant to the 105 frequency of the electromagnetic waves, the energy of which is to be received, and a self-restoring electric translating device adapted to utilize in its operation the kinetic energy of the current developed in said resonant circuit in combination with a source of 110 maintained or persistent electromagnetic radiation at a sending-station.

In testimony whereof I have hereunto subscribed my name this 31st day of July, 1902.

JOHN STONE STONE.

Witnesses:

CHARLES C. KURTZ,
ELLEN B. TOMLINSON.

It is hereby certified that in Letters Patent No. 737,170, granted August 25, 1903, upon the application of John Stone Stone, of Cambridge, Massachusetts, for an improvement in "Apparatus for Selective Electric Signalling," errors appear in the printed specification requiring correction, as follows: In line 6, page 3, the word "constance" should read *constants*; in line 35, page 6, the formula $\frac{I^2}{2 C}$ should read $\frac{I^2}{2 C p^2}$, and in line 50, page 7, $\pi/4$ should read $\pi/4$; and that the said Letters Patent should be read with these corrections therein that the same may conform to the record of the case in the Patent Office.

Signed and sealed this 8th day of December, A. D., 1903.

[SEAL.]

F. I. ALLEN,
Commissioner of Patents.
